LAMP SHADE

Herbert A. Plassman, Wauseon, Ohio, assignor to Fostoria Corporation, Fostoria, Ohio, a corporation of Ohio

Filed Feb. 12, 1960, Ser. No. 59,371

Term of patent 14 years

(Cl. D48—16)

Fig. 1 is a front elevational view of a lampshade, showing my new design;

Fig. 2 is a side elevational view thereof;

Fig. 3 is a cross-sectional view taken along line III—III in Fig. 1 or Fig. 4;

Fig. 4 is a top plan view thereof.

I claim:

The ornamental design for a lampshade, substantially as shown.
